UNITED STATES PATENT OFFICE

PAUL J. CLARK, OF LONGPORT, NEW JERSEY

PLATEN FOR PRINTING MACHINES

Application filed November 20, 1930. Serial No. 496,843.

My invention relates to platen mechanism for use with check endorsing machines or the like and while intended to apply to any machine to which it is adapted, is believed to have its widest application with check endorsing machines and has therefore been illustrated with this type of machine.

A purpose of my invention is to lengthen the effective life of the platen of a machine of the character indicated by the use of different resilient cover materials along different portions of the length of the platen.

In a continuously driven platen that functions to rotate a printing roll each time a check or the like is presented between the continuously driving platen roll and one or more suitable rider rolls engaging the platen, a further purpose is to provide the platen with a rubber surface for engagement with the type of the printing roll and with a cork surface or the like over that portion of the roll that drives the printing roll and preferably also over that portion thereof that drives the rider roll or rolls.

A further purpose is to lessen the effect of intermittent blows upon a rubber platen used to receive the type portions of a printing roll whenever a check or the like is passed between the printing and platen rolls, using a resilient buffer surface such as cork between the driving surfaces of the platen and printing rolls.

Further purposes will appear in the specification and in the claims.

I have elected to show two only of the many different forms of my invention, selecting however forms that are practical and efficient in operation and which well illustrate the principles involved.

Figure 1 is a sectional elevation through an endorsing machine of the type disclosed and described in my U. S. Patent No. 1,709,897, filed March 29, 1927 and entitled "Check endorsing machine", the view omitting some of the parts irrelevant to the present invention but described in the patent, and showing also partly diagrammatically electrical connections for bringing a printing roll into operation each time a check or the like is passed into the machine.

Figure 2 is a top plan view of Figure 1, partly sectioned and broken away to illustrate mechanism embodying my invention.

Figure 3 is a front sectional elevation of structure shown in Figure 1, omitting casing structure in order to more clearly show the roll mechanism.

Figure 4 is a horizontal section taken upon the line 4—4 of Figure 1.

Figure 5 is a fragmentary detail view to illustrate the application of my invention to a different type of mechanism from that shown in Figures 1 to 4, the parts being shown in position to receive a check for endorsing operation.

Figure 6 is a view corresponding generally to Figure 5 but with the rolls advanced by reason of the check shown entering the machine in Figure 5 having passed partly through the machine in Figure 6.

Figure 7 is a reduced scale top plan view of the structure shown in Figures 5 and 6.

Like numerals refer to like parts in all figures.

Describing in illustration and not in limitation and referring to the drawings:—

Referring to the structure illustrated in Figures 1 to 4, a platen roll 10 is continuously driven in any suitable way, illustrated as from a motor 11 through a spring clutch 12 and worm mechanism 13, Figure 4.

The platen roll is shown as including a shaft 14 operatively connected to the motor, and carrying spaced hubs 15 and 16, that in turn carry metal tubular structure 17 with resilient non-metallic cover portions 18, 19 and 20 along different portions of the length of the roll. The roll shaft is journaled in suitable stationary framework 23, being rotated continuously by the motor 11.

One or more feed or rider rolls 24 normally resiliently engage and are continuously driven by the platen which is also engaged by and rotates a printing roll 25 each time a check 26 is passed between the rider or feed rolls and the platen.

The feed or rider rolls 24 are resiliently pressed continuously against the surface of the platen roll being journaled at 27 on the spaced arms of a rocker 28 which is pivoted at

29 and spring pulled at 30, Figures 1 and 3, to press the rolls 24 against the platen roll.

The printing roll 25 is journaled in bearings 31 and 32 at the outer ends of spaced 5 horizontal arms 33 and 34 of a bell crank rocker 35.

The bell crank rocker 35 is pivotally supported at 36 and includes a downwardly extending arm 37 to which is pivotally connected at 38 a horizontal link 39 that carries near its forward end an armature 40 of an electric magnet 41.

The electro-magnet 41 is stationary and suitably carried from the frame structure of 15 the machine, being shown fastened by screws 41' to a bracket 41² that is in turn fastened by screws 41³ to projecting lugs 41⁴ of the frame (see Figures 1 and 3).

The outer end of the link 39 is vertically 20 supported and horizontally guided at 42 where a forwardly projecting horizontal rod 43 of the link slides through a perforation of a bracket 44, and is spring pressed adjustably forward at 45.

25 The link 39 is normally pressed forward from the position shown in Figure 1 to a position such that a felt 46 upon a forwardly directed surface of the link engages a rearwardly directed face of the supporting and 30 guiding bracket member 44.

Mechanism is provided for energizing the 35 stationary electric magnet 41 by the entry of a check or the like between the feed and platen rolls, the magnet then pulling its armature 40 and therefore the link 39 horizontally to the right, Figure 1, thereby moving the bell crank rocker 35 to bring the printing roll 24 down upon the platen 10 or rather upon the intermediate check 26 then passing 40 between the feed and platen rolls and supported from downward movement by the platen.

The strong pull of the magnet 41 presses 45 the printing roll strongly down upon the platen or intermediate check supported from downward movement by the platen with the result that the continuous drive of the platen then rotates the printing roll to effect the endorsement operation on the check.

50 The mechanism for closing the circuit of the magnet when the check enters between the feed and platen rolls includes a light detector rocker member 47 which includes a metal strip pivoting at end lugs 48 on a transverse 55 horizontal rod 49, with diagonally upwardly extending operating detector arms 50 and 51 registering within end grooves 52 and 53 of the platen roll 10 and an arm 54 registering within an intermediate groove 55 of the 60 platen roll.

The detector rocker 47 also includes a downwardly extending arm 56 which carries a contact 57 adapted to engage a cooperating contact 58 if the rocker is deflected, as by reason of the entry of a check between the feed and

70 platen rolls, the entering check engaging and downwardly pressing the upper ends of the arms 50, 51 and 54 of the detector rocker to close the contacts 57 and 58 and thereby to close the circuit of the electric magnet 41, as from an energy source 59 through the wire 60, the closed contacts 57 and 58 to one terminal 61 of the magnet and thence through the magnet and the other terminal 62 thereof to the other side of the energy source 59.

75 The detector rocker 47 is resiliently pulled at 63 to maintain a position such that its three arms 50, 51 and 54 within the circumferential grooves 52, 53 and 55 of the platen project forward diagonally upward into the 80 line of travel of the checks.

The printing roll 25 is designed to make one complete revolution each time a check passes between the feed and platen rolls.

85 It will be understood that the width of checks is variant and that the end of the rotary movement of the printing roll is determined by the breaking of the circuit of the electro-magnet 41, the spring at 45 then retracting the link 39 longitudinally to the 90 left which angularly moves the rocker 35 in a direction to carry the printing roll away from the platen.

95 The printing roll has a circumference somewhat greater than the width of the 95 widest check with which the machine is to be used and the contact breaking is effected by a cam surface 64 on the printing roll.

The cam 64 is formed to continue to depress the intermediate detector arm 54 after 100 the check has completed its passage between the rolls until the printing roll has completed a single revolution at which time the cam 64 releases the detector arm, permitting the spring retraction of the detector rocker 47 105 to open the circuit of the magnet which in turn permits the spring retraction of the printing roll away from the platen.

110 Each time a check is passed through the feed and platen rolls, it must in passing to a point between the print and platen rolls depress the detector arms 50 and 51 and 54 into their respective grooves 52, 53 and 55, the depression of the detector closing the electric 115 circuit of the magnet 41.

120 The energizing of the magnet 41 brings the printing roll sharply down upon the advancing check with a resilient pressure between the print and platen rolls that is adequate to frictionally drive the print roll by 125 the turning of the platen.

The opening of the magnet circuit at the end of one complete revolution of the printing roll, as determined by the cam 64 of the print roll releasing the detector arm 54, lets 125 the print roll retract from the platen, as already explained.

I find in practice the platen surface material registering with the type on the printing roll is desirably rubber, the character of 130

the printing being much better when the impression is supported by rubber than when supported by other materials, such for example as cork.

5 After continued service the rubber that supports the endorsement impressions deteriorates, bulging outwardly at the portion of the platen roll that registers with the printing roll.

10 I have discovered that this deteriorating bulging of the rubber on the portion of the platen that registers with the printing portion of the printing roll may be greatly delayed with a consequent great increase in the 15 life of the platen, by using cork or like material instead of rubber as a circumferential covering on driving portions of the platen not registering with the printing portion of the printing roll.

20 In the past the platen has presented rubber not only to the printing portion of the print roll but also to nonprinting portions of the print roll and to the feed rolls, with the life of the platen determined by the gradual 25 bulging deterioration of rubber at the printing portion of the print roll.

By my invention I make no change in the portion of the platen that registers with the endorsement type but greatly increase its life 30 and thereby the life of the platen by using cork along the remaining engagement portion of the platen.

While the reason for this material increase in the life of the rubber at the middle of the 35 platen from changing the character of the platen surface material elsewhere than at the middle is not altogether clear, the applicant believes it is due to a combination of causes including a deadening by the cork of inward 40 vibration movements existent when rubber is used on all the driving surfaces of the platen, and also the mere shortening of the rubber on the platen, with a resultant lessening of bulging incident to longitudinal expansion 45 due to a gradual lessening of the rubber density during prolonged wear.

Whatever the true reason the fact appears that changing the covering on the portion of the platen that does not register with the 50 type has a very material effect in increasing the life of the part of the platen that does register with the type on the print roll.

As best seen in Figures 3 and 4 I preferably limit the surface rubber on the platen roll to 55 that portion 19 thereof that registers with the type 66 on the printing roll and provide the end portions 18 and 20 of the roll on each side of this intermediate portion with a cover that is desirably cork but may be similar material having characteristics adapting it to 60 deaden the inward movements of the type portion of the printing roll with respect to the rubber surface presented by the platen.

In the form shown in Figures 5 to 7, the 65 platen roll 67 is driven as before continuously

in any suitable way, not shown. The feed rolls 68 and printing roll 69 are mounted between the spaced arms 70 and 71 of a common rocker 72 journaling respectively in bearings 73 and 74 that may be relatively rigid portions of the rocker 72.

The rocker has a horizontal pivot support at 75 and 76 in stationary frame structure 77.

Normally the feed rolls 68 are in engagement with the platen roll, rotating continuously by frictional engagement with the platen.

When a check 26 is inserted between the feed and platen rolls, its forward edge in passing between the rolls engages the lower end of a trip lever 78 and secures a single rotation of the print roll by deflecting the trip lever in pushing past this lever.

The trip lever extends diagonally downwardly from a pivot 79 carried by an upwardly projecting portion of the rocker 72, has a link connection 80 with the upper end of a latch member 81 and has a downwardly projecting toe that extends into a circumferential groove 82 of the platen.

The latch member 81 is pivotally supported at 83 on the rocker 72 and normally presents a hook surface 84 against an abutment 85 of the print roll, normally preventing turning movement of the printing roll, which in its normal position is resiliently pressed at 86 in its direction of rotation.

The print roll has a suitable flattening at 87 so that normally it is out of engagement with the revolving platen roll, the engagement between the feed roll and platen roll holding the rocker 72 from downward movement to bring the print roll against the platen.

As soon as an advancing check rearwardly deflects the trip lever, this lever swings back the latch 81, releasing the print roll to forward turning in the direction of the arrow, responsive to a suitable spring 88 pressing against the cam surface 86 presented by the print roll.

A small arcuate turning movement of the print roll effected by the cooperating action of the spring 88 and cam 86 brings the full radius portion of the printing roll into engagement with the platen or with the check passing between the platen and print rolls, turning the print roll flattening at 87 beyond the platen.

The engagement is now between the print roll and platen rather than between the feed roll and platen, the rocker arm 72 carrying both the printing and feed rolls lifting slightly to permit passage of the check and the print roll being driven frictionally by its engagement with the continuously revolving 125 platen.

As before the circumference of the print roll should be greater than the width of the widest check used with the machine.

After the check has passed through the ma- 130

chine and at the end of one complete revolution of the print roll, the print roll is brought to rest by the abutment 85 of the roll engaging the hook surface 84 of the latch 81, the print 5 roll coming to rest with its flattening 87 directed toward the platen to relieve engagement between the print roll and platen a little before the print roll stops against the hook and thereafter until the print roll has been 10 turned onward somewhat when the next check releases the latch.

It will be seen that the cutting away at 87 of the print roll permits the feed rolls to come strongly against the platen, the feed 15 rolls holding the rocker 72 out sufficiently to prevent the print roll from engaging the platen.

As in the other form, I provide the platen with an outer thickness of rubber at 90 where 20 it registers with the type portion 91 of the printing roll and with an outer cover of cork or the like material at 92 and 93 that engage the end portions of the printing roll and the feed rolls, the cork at the non-printing bearing surfaces effecting a material increase in 25 the life of the intermediate rubber presented to the printing portion of the printing roll.

In view of my invention and disclosure variations and modifications to meet individual whim or particular need will doubtless become evident to others skilled in the art, to obtain all or part of the benefits of my invention without copying the structure shown, and I, therefore, claim all such in so 35 far as they fall within the reasonable spirit and scope of my invention.

Having thus described my invention, what I claim as new and desire to secure by Letters Patent is:—

40 1. A platen having rubber along one portion of its length and cork along another portion of its length, a print roll for intermittent operation by the platen, and mechanism effecting driving engagement between the print roll and platen, the print roll having printing and non-printing portions engaging the platen respectively along the cork and rubber surfaces thereof.

45 2. A platen having rubber along one portion of its length and cork along another portion of its length, a feed roll making driving engagement with the platen along the cork thereof, a print roll for intermittent operation by the platen and presenting its printing surface in registry with the rubber of the platen and mechanism effecting driving engagement between the print roll and platen.

50 3. A platen having rubber along one portion of its length and cork along another portion of its length, a print roll having a printing portion registering with the rubber of the platen, a non-printing portion registering with the cork of the platen and a feed roll registering with the cork of the platen.

55 4. A platen having rubber and cork along

different portions of its length respectively for receiving a printing stroke and for making driving engagement with auxiliary mechanism.

5. In a machine of the character indicated, 70 a platen, means for continuously driving the platen, a rider roll engaging the platen and a printing roll including a type-carrying portion and end portions for making a driving connection with the platen, adapting the printing roll to be rotated by the platen each time a check is inserted, the platen having rubber at the portion that engages the printing portion of the print roll and cork at the end portions thereof that engage the printing 80 roll and rider roll.
